ROLL CRUSHER FOR SUCH METALS AS ALUMINUM AND ZIRCONIUM, WITH MEANS TO REDUCE THE STATIC CHARGES IN THE CRUSHER OUTPUT

Arthur A. Bernard, Chicago, Ill., assignor to National Cylinder Gas Company, Chicago, Ill., a corporation of Delaware

Application March 18, 1953, Serial No. 343,099.

5 Claims. (Cl. 241—159)

This invention relates generally to a crushing apparatus as well as an improved process of crushing granular material and more particularly to an improved device for reducing granular material to particles of predetermined uniform size without producing static charges on the comminuted material.

The apparatus of the present invention is particularly adaptable for producing comminuted particles to be supplied to particle feeding systems which are required to feed accurate prescribed quantities of material. More specifically, the present apparatus is useful in providing a granular zirconium, aluminum or other compound for use with feeding systems of the type disclosed in co-pending applications Serial Nos. 343,097 and 343,098, filed concurrently herewith and assigned to the same assignee as the present invention. The crushing apparatus herein described is suitable for any crushing process wherein it is desired to produce particles of predetermined uniform size or wherein it is desirable to produce particles which are not electrostatically charged by the crushing operation.

The prevalent commercial practice in supplying granular material for use with accurate feeding devices is to crush particles which are several times larger than those desired in the feeding apparatus in order to permit reduction of the particles to the desired size. In most cases, the larger particles which are to be crushed are obtained from commercial supply houses and are ordered therefrom in bulk form. The bulk material contains an appreciable percentage of small particles which have been reduced in size by vibration, handling of the bulk material, and other similar operations which occur in transit. Generally, the prior systems for reducing the size of the particles of the bulk material have involved ball mill or hammer mill type pulverizing equipment to which the bulk material is fed. The grinding hammers or crushing balls of the prior apparatus reduce the size of all of the particles in the bulk material, including the particles which are small enough or too small, by repeated blows applied to the material fed to the equipment. It is therefore apparent that the ball and hammer crushers act upon the smaller particles of the bulk material which have already been reduced to the desired size, whereby the size of these particles is reduced beyond that which is desired. The constant pounding of the granular material reduces a portion of this material to dust or powder comprising minute particles and, for many purposes, the presence of these minute particles in the output of the crusher is highly undesirable. For this reason, the detritus output of the prior art crushers has consisted of particles which are not uniform in size and which contain a considerable quantity of triturated particles.

A further disadvantage of these prior systems has been the introduction of electrostatic charges to the comminuted particles by the excessive friction induced by repeated pounding and beating of the bulk material. The amount of static charge induced is directly determined by the frictional forces to which the material is subjected

2

in the crusher. The crushing of the small particles below the size which is actually desired results in the application of frictional forces to these particles thereby creating an unnecessary source of static charges. The granulated particles appearing in the output of the prior systems are therefore electrostatically charged so that when these particles are supplied to a feeding system, the particles tend to cling together and adhere to the walls of the feeding apparatus. Under these conditions it is virtually impossible to feed accurate measured quantities of the material through the feeding mechanism.

The present invention obviates these difficulties by providing a crushing apparatus which includes a plurality of aligned crushing rollers cooperating in pairs to comminute material which passes therebetween. The paired rollers are spaced a small distance apart so that those particles of the bulk material which are smaller than the space between the rollers pass directly through the crusher without comminution. Thus, the smaller particles are not reduced in size and the detritus output of the crushing apparatus contains a minimum of dust and powdered material. All particles of the bulk material which are larger than one of the spaces between the paired rollers are crushed and reduced to a size which closely approximates the spacing between the rollers. The granular particles in the output of the crusher are therefore maintained at a uniform size and, by adjusting the spacing between the rollers, this size may be varied to obtain particles of any desired size. The passage of the smaller particles directly through the crushing apparatus reduces by an appreciable extent the amount of material subjected to frictional contact and the static charges induced in the output of the crusher are thereby minimized. The crushing of material between the rollers avoids the necessity of repeated pounding and reduces the frictional contact thereby, greatly reducing the static charges produced in the crusher output. As soon as the bulk material is reduced to a size which allows the particles to pass between the smallest space between the rollers, the particles pass directly through the crusher without further frictional contact with the crushing mechanism. In this manner, contact between the particles and the apparatus is maintained at a minimum and the granular output of the crusher is free of charged particles so that the output is suitable for use with feeding systems which are required to deliver accurate quantities of material.

Accordingly, it is an object of the present invention to provide a crushing apparatus for producing particles of uniform size.

It is another object of the present invention to provide a crushing apparatus which reduces granular material to particles of predetermined size which are relatively free of dust and other powdered material.

A further object is to provide a crushing apparatus which reduces the size of particles with a minimum of frictional contact so that the output of the crusher is relatively free of electrostatically charged particles.

A still further object is to provide a crushing device in which particles smaller in size than those which are desired are passed directly through the crusher without comminution.

A still further object of the present invention resides in an improved process of reducing the size of granular material without subjecting the resultant product to undesirable electrostatic charges during the crushing operation.

Another object of the invention is to provide a crushing machine employing spaced rollers in which the spaces between the rollers permit particles below a predetermined size to pass through the rollers without comminution and in which particles larger than the spaces between the rollers are crushed so that uniform sized par-

ticles, free of static charge, are emitted from the crusher.

Further objects and advantages of the present invention will become apparent as the following description proceeds, and the features of novelty which characterize the invention will be pointed out with particularity in the claims annexed to and forming a part of this specification.

For a better understanding of the present invention reference may be had to the accompanying drawings in which:

Fig. 1 is a front elevational view of the crusher of the present invention having a portion of the front panel broken away to show the details of the driving connection for a crushing apparatus which is characterized by the features of the present invention;

Fig. 2 is a partial sectional view taken substantially on line 2—2 of Fig. 1 assuming that Fig. 1 shows the complete structure in order to show the details of the crushing mechanism;

Fig. 3 is a sectional view of the crushing mechanism taken along a line substantially corresponding to line 3—3 of Fig. 2, assuming that the entire crusher had been shown in Fig. 2;

Fig. 4 is a rear elevational view of the crusher of Fig. 1 having a portion of the rear panel broken away to show the details of the driving connection and the mountings for the crushers;

Fig. 5 is an enlarged sectional view taken along a line substantially corresponding to line 5—5 of Fig. 3, assuming Fig. 3 shows the complete structure, to show the feeding slot in the crusher;

Fig. 6 is a sectional view taken on line 6—6 of Fig. 5 and again assuming that the entire crusher had been shown in Fig. 5;

Fig. 7 is a sectional view taken along line 7—7 of Fig. 6, assuming Fig. 6 shows the complete structure, to show the details of a portion of the feeding mechanism which controls the flow of material to the crusher;

Fig. 8 is an enlarged broken-away portion of the apparatus of Fig. 4 showing the details of the mountings for the crushers;

Fig. 9 is a partial view similar to Fig. 4 but reduced in size illustrating a modification of the present invention;

Fig. 10 is an enlarged view of a portion of Fig. 9;

Fig. 11 is a sectional view taken on line 11—11 of Fig. 10, assuming that Fig. 10 shows the complete structure including a wall portion which was cut away in Fig. 9; and

Fig. 12 is a sectional view taken on line 12—12 of Fig. 10, again assuming that Fig. 10 shows the complete structure.

Referring now to the drawings, wherein like reference characters designate like or corresponding parts throughout the several views, there is shown in Fig. 1 a crushing apparatus indicated generally as 20 including a housing having a horizontal base 21 and a pair of parallel vertical front and rear panels 22 and 23, respectively, secured to the base in any suitable manner. The housing of the crusher is divided into upper and lower sections 24 and 25, respectively, by a wall 26 which is supported between the vertical front and rear panels and which is provided with a comminuted material delivery passageway 27 and a drive connection opening 27a, the purposes of which will become fully evident as the description proceeds.

The lower housing 25 is divided into a detritus receiving chamber 28, which is positioned below the material delivery passageway 27 so as to receive the output of a crusher mechanism indicated generally as 29, and a motor housing compartment 30, which encloses a driving source 31 for the crusher mechanism. A drive connection indicated generally as 32 interconnects the driving source and the crushing mechanism to supply power to the crusher. Particles of material are fed to the crusher from a granular material storing hopper 34 by a flow regulating feed mechanism 33 which supplies material

to be comminuted in a manner to be subsequently described in more detail.

In order to provide an enclosed lower housing, the lower section 25 of the crusher includes parallel side panels 35 and 36 which interconnect the parallel front and rear panels and are secured to the base 21 and to the separating floor or wall 26. The enclosed lower housing thus formed may be divided by a transverse vertical compartmenting plate 37 into the detritus receiving chamber 28 and the motor housing compartment 30. To permit access to the detritus receiving chamber, the side panel 36 may be provided with an access door 28a hinged on the side panel in any suitable manner. The access door facilitates the removal of the comminuted output of the crushing mechanism 29 which is deposited in the detritus receiving chamber. The driving source 31, which may be of any suitable type, is shown in Figs. 1 and 2 as an electric motor which is supported in a position adjacent to the upper housing by a motor supporting floor 38 extending parallel to the base floor 21 within the motor housing compartment 30. The positioning of the driving source near the upper housing and near the crushing mechanism 29 avoids the necessity for extended driving connections between the upper and lower housings and, hence, simplifies the mechanical structure of the drive connection 32.

The upper housing 24 includes a vertical side wall 39 which is secured to the separating floor 26 and extends upwardly to form one side of an enclosed crushing chamber 40 for the crushing mechanism. Also secured to the separating floor and extending upwardly are a pair of parallel chamber-forming plates 41 and 42 which are positioned perpendicular to the side wall 39 so that a compartmenting wall 43a which joins the chamber-forming plates completes a rectangular enclosure to form the crushing chamber 40 in the upper housing. The parallel plates 41 and 42 extend upwardly beyond the crushing chamber 40 in order to form two sides of the hopper 34 and are provided with a plurality of shaft positioning apertures 41a for purposes which will subsequently appear evident. The front panel 22 cooperates with the parallel plate 41 and the side wall 39 to form a gear train housing 43 for encasing a driving gear train mechanism indicated generally as 44. The gear train housing 43 serves to protect the moving parts enclosed therein from dirt and moisture, and in addition serves to protect the clothing and limbs of the crushing machine operator from entanglement with the gear train. For protection against similar hazards, the rear panel 23 cooperates with the parallel plate 42 and the side wall 39 to form an enclosed driving assembly housing 45 which extends the entire width of the parallel plate 42 and encases a portion of the driving connection 32 between the driving source 31 and the crushing mechanism.

As was indicated above, the hopper 34 is positioned above the crushing chamber 40 by the parallel plates 41 and 42 which constitute two sides of the hopper, the other two sides of which are formed by the side plate 39 and by a hopper-forming partition 46 extending between the parallel plates. The hopper may be provided with a pair of converging bottom sections 47 which form a trough for feeding the granular material from the hopper through an elongated slot or rectangular opening 48 in the bottom of the hopper. The converging bottom sections of the hopper are terminated by a pair of material guiding members 49 which extend through an elongated slot in a partitioning floor 50 between the hopper and the crushing chamber 40 so as to guide material from the hopper to the crushing chamber.

To facilitate the feeding of material from the hopper to the crushing mechanism 29, the flow regulating feed mechanism 33 is positioned below the elongated opening 48 in the hopper. This mechanism includes a material retaining leaf 51 and a slotted material feeding plate 52 which are contiguous with the guiding members

49 and which extend downward from the partitioning floor 50 into the crushing chamber. As best shown in Fig. 6 the material-retaining leaf 51 is provided with an end strip 53, which may be of felt or other non-abrasive material, in contact with a material distributing feed roller 54. The slotted material feeding plate is positioned closely adjacent the feeding roller 54 near the opening 48 in the hopper so that material which drops from the hopper onto the feed roller passes through a plurality of slots 52a formed in the bottom of the plate 52 as best shown in Fig. 7. By varying the number and size of the slots in the material feeding plate, the rate of flow of material to the crushing mechanism 29 may be controlled.

For the purpose of supporting the feed roller 54 the latter is mounted on a rotatable feed roller shaft 55 which extends between the side plates 41 and 42 and fits within one of the shaft receiving apertures 41a in each of said side plates. Secured to each of the side plates in order to journal the ends of the feed roller shaft 55 which extend through the shaft receiving apertures are a pair of feed roller bearing assemblies 56. A feed roller gear 57 which is one element of the gear train 44 is mounted on the feed roller shaft 55 in order to impart the movement of the gear train to the feed roller.

Vertically aligned with the feed roller 54 are a plurality of rotatable crushing rollers 58a, 58b and 58c, the axis of each of which is fixed and which axes are spaced from one another. The crushing rollers are mounted on crushing roller shafts 59a, 59b and 59c, respectively, which are vertically aligned with the feed roller shaft 55 and which extend through the shaft receiving apertures in the parallel plates 41 and 42. The roller shafts 59a and 59c, respectively, are identical in construction but the shaft 59b is somewhat longer than the shafts 59a and 59c in order to accommodate a sprocket wheel 68, the operation of which will be described in detail in the ensuing description. Each end of the crushing roller shafts is rotatably journaled within a fixed bearing assembly 64 rigidly mounted on the parallel plates. On the end of each of the roller shafts 59a, 59b and 59c extending through the bearing assembly and into the gear train housing 43 are mounted crushing roller gears 65a, 65b and 65c of the gear train 44. The crushing roller gears are vertically aligned with the feed roller gear 57 and are operably interconnected with the feed roller gear by pinion gears 66a, 66b and 66c which are secured to pinion gear shafts 67 rotatably mounted within shaft positioning apertures in the side plate 41. The pinion gear 66a simultaneously meshes with the feed roller gear 57 and the upper crushing roller gear, whereas each of the other two pinion gears 66b and 66c simultaneously meshes with two of the crushing roller gears, thereby completing the interconnection of the feed roller and the crushing rollers.

A plurality of adjustably mounted rotatable crushers 76a, 76b and 76c are vertically aligned and spaced within the crushing chamber 40 in a position in which the adjustably mounted rollers are horizontally aligned with the fixed roller crushers 58a, 58b and 58c, respectively. The adjustable roller crushers 76a, 76b and 76c are, respectively, mounted on roller crusher shafts 79a, 79b and 79c, each of which is rotatably journaled within adjustable bearing assemblies 80 secured to the parallel plates 41 and 42. The bearing assemblies 80 are secured to the parallel plates by detachable retaining bolts 81 which may be loosened to permit the adjustable rollers to be moved toward or away from the fixed rollers for purposes which will hereinafter be clearly explained.

In order to interconnect the adjustable roller crushers with the gear train 44, the shafts 79a, 79b and 79c are provided with roller crusher gears 82a, 82b and 82c, respectively, which mesh with the roller crusher gears 65a, 65b and 65c, respectively, within the gear train 75

housing 43. In this manner a plurality of aligned pairs of rotatable crushing rollers are provided within the crushing chamber in which the axis of one of each pair is fixedly mounted between the parallel plates and the axis of the other is movable toward or away from the fixedly mounted roller axis. In accordance with the present invention, the fixed roller of each pair is spaced a small distance from the adjustable roller so that material which is fed thereto from the flow regulating mechanism 33 may pass between the rollers to be crushed. Preferably the spacing between the upper pair of rollers 58a and 76a is larger than the spacing between the other pairs and the spacing between each successive pair of rollers becomes decreasingly smaller. That is, the spacing between the rollers 58a and 76a is larger than the spacing between rollers 58b and 76b which, in turn, is larger than the spacing between rollers 58c and 76c. Although three pairs of rollers are illustrated in the drawings, it is obvious that any number of pairs may be utilized depending upon the type of material to be crushed and the size of particles desired.

It now becomes apparent that as the material is fed to the first pair of crushing rollers 58a and 76a from the flow regulating mechanism 33, all particles of the material which are smaller than the spacing between the rollers fall directly through the spacing without being crushed, whereas all particles larger than the spacing are crushed by the rotation of the rollers. All particles which pass without comminution through the spacing between the first rollers and the particles which are comminuted by the first rollers flow successively to the other pairs of rollers 58b and 76b, and 58c and 76c. Those particles in the hopper which are smaller than the smallest spacing between any of the roller pairs will pass through all of the rollers without comminution. In this manner all particles in the hopper which have previously been reduced to small size by handling and transportation effects flow directly through the crusher and are not reduced to powder or dust. Another important effect of passing the small particles through the crusher without comminution is that the static charges induced by frictional contact between the particles and the rollers is reduced to a minimum. The presence of charged particles in the output of the crusher makes the comminuted material very difficult to handle in that these particles tend to adhere to the surfaces of feeding mechanisms in which they are subsequently placed for distribution.

The spacing between each pair of rollers may be adjusted by loosening the retaining bolts 81 and moving the bearing assemblies 80. As the bearing assembly is moved, the bolts 81 slide within elongated slots 81b in the parallel plates thereby moving the adjustable roller shaft within the slots 81a until the rollers are separated by the desired spacing. The retaining bolts 81 may then be tightened to lock the bearing assembly 80 and the adjustable roller in the desired position. Repeated crushing of non-friable material results in a gradual wearing of the roller surfaces so that it becomes necessary to set the rollers periodically to the required spacing in order to compensate for the wear. Wear on the roller surfaces may be corrected by simply adjusting the bearing assembly 80 in the manner heretofore described. Eventually, after repeated adjustments, the length of the teeth on the meshing crusher roller gears limits the movement of the adjustable roller towards the fixed roller. When the gear teeth limit the movement of the adjustable roller, simply adjustment of the roller position no longer corrects for the erosion of the surface and it becomes necessary to replace the rollers.

From the foregoing description it is obvious that if it is desired to crush a friable material, only one or two pairs of crushing rollers may be required and the spacing between the rollers may be very small. On the other hand, if non-friable particles are to be comminuted, several pairs of crushers are preferably used in which the

spacings between the pairs are reduced very gradually.

In order to remove any particles which tend to adhere to the surface of the rollers, the feeding roller and each of the crushing rollers is preferably provided with a particle removing wiper blade as shown in Fig. 3. The wiper blade for the feeding roller is designated 83 whereas the wiping blades for the crushing rollers are designated 83a, 83b and 83c. Each of the wiper blades is mounted on a wiper blade shaft 84 which extends through shaft receiving apertures in the parallel plates 41 and 42 adjacent the surface of the rollers. Each of the wiper blades is normally maintained in contact with the surface of one of the rollers by a resilient member 85 which is secured between an extending lip 86 of the shaft 84 and the parallel plates 41 and 42. The wiper blades 82a and 82b free the rollers of material which clings to the surface and direct the freed material to the next succeeding pair of rollers. The wiper blades 82c for the rollers 58c and 76c direct the freed particles through the comminuted material delivery passageway 27 and into the detritus receiving chamber 28.

The driving connection 32 includes the sprocket wheel 68 mounted on the crushing roller shaft 59b and operably connected to the driving source 31 through a driving chain 69 and a belt 70. The belt 70 interconnects a small pulley wheel 71 mounted on armature shaft 72 of the motor and a large pulley wheel 73 mounted on a remotely driven shaft 74 which is positioned parallel to the armature shaft within the shaft receiving apertures in the parallel plates 41 and 42. The remotely driven shaft is rotatably journaled within suitable bearing assemblies, not shown in the drawings. One end of the driven shaft extends through the parallel plate 42 and into the driving assembly housing 45 so that the large pulley wheel 73 may be mounted thereon. The driven shaft extends from the housing 45 through the parallel plates 41 and 42 and into the gear train housing 43 where a small sprocket wheel 75 is mounted on the end of the shaft. The interconnection of the pulley wheels on the armature shaft and the remotely driven shaft by the belt 70 transmits the rotary movement of the driving source to the driven shaft and to the small sprocket wheel 75. The driving chain 69 meshes with the sprocket wheel 68 within the gear train housing and with the small sprocket wheel 75 thereby completing the transmission of driving torque from the motor to the crushing mechanism. The rotation of the sprocket 68 by the driving source 31 in the manner just described causes the crushing roller shaft 62 to drive each of the intermeshing gears 57, 65a, 65b, 65c, 66a, 66b, 66c, 82a, 82b and 82c of the gear train 44. The rotation of each of the gears in the gear train induces rotation of the shafts on which the gears are mounted thereby causing the crushing rollers and the feeding rollers to turn in the direction of the arrows shown in Fig. 3. The feeding roller 54 and the crushing rollers 58a, 58b and 58c are rotated about fixed axes in a clockwise direction as viewed in Fig. 3 whereas the adjustable crushing rollers 76a, 76b, and 76c are rotated in a counterclockwise direction.

In the overall operation of the crushing mechanism, bulk material usually of the type containing granular elements of varying size, is placed in the material storing hopper 34. The granular material in the hopper flows through the elongated slot 48 in the bottom of the hopper, along the guide members 49 and over the feeding roller. Energization of the driving source causes the feeding roller and the crushing rollers to be continuously rotated at constant speed. The material falling onto the feeding roller is fed through the plurality of slots 52a in the material feeding plate 52 and falls onto the fixed roller 58a and the adjustable roller 76a. The rate of flow of material to the crushing rollers may be regulated to any desired amount by exchanging the material feeding feeding plate for one having a different number of slots or for one having slots of different sizes. The rate

of flow of material to the rollers is preferably adjusted so that granular material will not pile up on the rollers thereby insuring an even flow of material through the crushers 58a and 76a. The material retaining leaf 51 prevents the granular material from falling from the feeding roller and into the crushing chamber 40 without passing through the crushing rollers.

The particles of material are fed through the material feeding plate 52 to the first pair of spaced rollers 58a and 76a where all particles of material smaller than the spacing between the rollers are passed therethrough without comminution and all particles larger than the spacing are crushed by the rollers. A large number of the particles crushed between the first pair of rollers are reduced to a size commensurate with the spacing. The output of the first pair of rollers thus comprises a large number of particles of a size corresponding to the spacing between the crushers and a relatively fewer number of particles which are smaller than that spacing. This output is applied to the second pair of rollers 58b and 76b where the crushing operation is repeated by allowing all particles smaller than the spacing between the second pair of rollers to pass un molested. The spacing between the second pair of rollers is somewhat less than the spacing between the first pair so that the large number of particles which were reduced to a size equal to the spacing between the first pair are again crushed by the second pair of rollers. Most of the particles are reduced by the second pair of rollers to a size identical with the spacing therebetween so that the output of the second pair consists of many particles of material equal in size to the spacing between the second pair of rollers and a smaller number of particles of a size less than that spacing. The crushing operation is repeated in the third pair of rollers 58c and 76c in which nearly all of the particles are reduced to a uniform size which is equal to the spacing between the third pair of rollers. Thus each pair of rollers is spaced at a distance corresponding to the size of the particles to be comminuted therebetween in order that the output of the final pair of rollers comprises particles of uniform size. The output of the final pair of rollers flows through the comminuted material delivery passageway 27 and into the detritus receiving chamber 28 in the lower housing.

Some of the granular elements in the storing hopper 34 have been reduced by vibration, jarring and handling to a size which is equal to or somewhat less than the spacing between the final pair of rollers. All of these particles pass directly through the material feeding plate 52, through the spacings between all of the pairs of rollers and into the detritus receiving chamber without comminution. Therefore those particles which equal or are less than the uniform size desired are passed directly to the output of the crusher and are not reduced below this desired size by the crushing mechanism. The particles of material which are reduced by one of the pairs of rollers to a size equal to or less than the spacing between the final pair of rollers pass directly to the detritus receiving chamber without further crushing action. In this manner, frictional contact between the particles and the crushing mechanism is minimized and the output in the detritus receiving chamber is free of static charges. The detritus output of the crusher is also free of material which is reduced to dust or powder.

The adjustable bearings 80 permit the spacings between the rollers to be varied in accordance with the material to be crushed or to compensate for changes in spacing due to the wear on the roller surfaces. The output of the crusher which is stored in the detritus receiving chamber 28 may be removed in any convenient manner. As shown in Figs. 1 and 2, the chamber may be provided with an access door 28a through which the output is removed. However, any collecting means well known in the art may be utilized with the crushing mechanism of the present invention. It is obvious that a ma-

terial receiving bucket may be attached to the access door if desired, or the detritus receiving chamber may be in the form of a slideable drawer from which the material may be readily removed.

From the above description it will be apparent that there has been described an arrangement in which the crushing roller shafts 79a, 79b and 79c are adjustable relative to cooperating crushing roller shafts 59a, 59b and 59c, respectively. In Figs. 9 to 12 of the drawings there is illustrated a modification of the means for adjusting the positions of shafts 79 relative to the shafts 59. The corresponding parts of Figs. 9 to 12 are designated by the same reference numerals as in the preceding embodiments. As there illustrated, each of the bearing assemblies 64 is illustrated as being mounted on a flat plate 91, which in a particular embodiment constructed in accordance with the present invention comprised a square plate about 4 inches square. Similarly, each of the adjustable bearing assemblies 80 is mounted on a flat plate 90, preferably identical with the flat plate 91. With this construction there is defined a space between the corresponding flat plates 90 and 91 associated with a pair of crushing rollers for accommodating a leaf spring 92 tending to bias the bearing assemblies 64 and 80 apart.

For the purpose of supporting the bearing assemblies associated with the flat plate 90 for relative movement with respect to the bearing assemblies 80, or, in other words, for the purpose of providing floating bearings associated with the adjustable crushing rollers 76, a slide arrangement for each floating bearing is defined by members 93 and 97 which are suitably secured to the wall 42 by the fastening means 98. In order properly to adjust the bearing assemblies 80 in any desired relationship with respect to the bearing assemblies 64, suitable adjustable means are associated with the wall 39 comprising a nut member 94 preferably welded to the wall 39 for threadedly receiving an adjustable screw member 96 engageable with the plate 90. A suitable lock nut 95 insures that any adjustment which is made is properly maintained. With the arrangement described it will be apparent that the spring 92 constantly biases the floating bearing against the screw 96, and the space between the crushing rollers may be increased by withdrawing the screw 96, or increased by the opposite operation of the screw 96 in a manner that will be readily apparent.

For purposes of illustration, the crushing apparatus of the present invention will now be described in accordance with its embodiment when used for supplying zirconium compound particles for the feeding mechanism disclosed in copending applications Serial Nos. 343,097 and 343,098. As explained in these applications, zirconium is a very hard and brittle material, and when subjected to crushing forces is easily charged by the friction of the crushing process. The requirements of the feeding system are such that accurate amounts of zirconium compound must be delivered through the feeding mechanism. If the zirconium material accumulates static charges as the compound is crushed, particles of the material tend to adhere to the surfaces of the feeding apparatus and accurate delivery is impossible.

Ordinarily the zirconium compound is purchased in granular bulk form designated as 8 mesh in which each particle is at least $\frac{1}{8}$ of an inch in diameter. The feeding mechanism of the aforementioned applications is designed for use with 40 mesh compound and, therefore, it is necessary to reduce considerably the size of the particles in the 8 mesh compound. The 8 mesh compound is placed in the hopper 34 and flows through the regulating mechanism 33 to the first pair of rollers 58a and 76a. The slots 52a of the material feeding plate 52 are approximately $\frac{1}{4}$ of an inch wide and $\frac{5}{32}$ of an inch high, so that even the largest particles of the 8 mesh material readily flow through the slots. The first pair of rollers are spaced about $\frac{3}{32}$ of an inch apart in order to comminute all particles in the compound which exceed $\frac{3}{32}$ of an inch in size,

whereas all particles smaller than $\frac{3}{32}$ of an inch pass through the first rollers without being crushed. The second pair of rollers 58b and 76b are spaced about $\frac{3}{64}$ of an inch apart in order to crush all particles in the output of the first pair of rollers which exceed this size. The spacing between the final pair of rollers is adjusted to $\frac{1}{16}$ of an inch to produce a 40 mesh zirconium compound in which the particles are of uniform size. Since zirconium is a non-friable material, the rollers must be of sufficient hardness to withstand considerable wear in order to avoid the necessity for frequent replacement. To this end the rollers are formed of vanadium tool steel which is case hardened to produce a durable surface having a long operating life. Obviously, the material of which the roller is made, depends upon the friability of the material to be crushed.

All of the particles of the granular compound in the hopper which were originally smaller than $\frac{1}{16}$ of an inch pass through all of the rollers without being crushed, hence avoiding the aforementioned difficulties with respect to trituration and electrostatic charges. All particles between $\frac{1}{16}$ of an inch and $\frac{3}{64}$ of an inch are subjected only to the crushing operation of the rollers 58c and 76c, and by this means the frictional forces producing electrostatic charges are minimized. Particles between $\frac{3}{64}$ of an inch and $\frac{3}{32}$ of an inch may be subjected to only one or two comminuting actions depending upon the size to which the particles are reduced by the first action. It is manifest that the crushing operations to which each particle is subjected are maintained at a minimum in order to reduce friction and prevent the formation of dust and other minute particles.

From the foregoing explanation it is apparent that the present invention affords a satisfactory solution to the problem of producing in the output of a crushing apparatus particles of uniform size which are free from dust and powder, and which are not electrostatically charged.

It is to be understood that the foregoing description is pertinent only to a preferred embodiment of the invention to illustrate the principles thereof. Obviously, many modifications and variations of this invention are possible in the light of the above teachings. It is intended by the appended claims to cover all modifications and variations which fall within the true spirit and scope of the present invention.

45 What is claimed as new and desired to be secured by Letters Patent of the United States is:

1. In a crushing apparatus for producing particles of predetermined uniform size from bulk material having elements of varying size without electrostatically charging the particles produced, the combination of a housing, a container having an opening through which particles of varying size flow, a plurality of aligned cooperating pairs of rollers positioned within the housing and below the opening, each pair of rollers having a spacing therebetween corresponding to the size of particles to be crushed, a distributing roller positioned adjacent the opening in said container for feeding the particles of varying size to a first pair of the cooperating rollers, a flow regulating plate rigidly mounted upon said housing and having a bottom edge positioned adjacent said distributing roller near the opening, the bottom edge of said plate being provided with a plurality of spaced apertures in order to feed the particles to said first pair of rollers at a preselected rate, the spacing between said first pair of rollers being much larger than the predetermined size particles to be produced so that only the largest of the varying size particles are comminuted by the first pair of rollers whereas all the particles except the large ones pass through the space without comminution successively to the other pairs of rollers, each of the spacings between the pairs of rollers being successively smaller than the spacing between the first pair of rollers so that each pair of rollers comminutes only those particles larger than the spacing therebetween, the last pair of rollers through which the particles pass being spaced apart a distance equal to the predetermined size

particles whereby all the particles below the predetermined size pass without comminution and all the particles above the predetermined size are reduced to the predetermined size, and a collecting means into which all of the particles flow after passing through the final pair of rollers, the spacing between each of the pairs of rollers permitting the passage of all particles in the container below the predetermined size to pass directly from the container through the rollers to the collector without comminution.

2. The combination of claim 1 including means for adjusting the spacing between each of the pairs of rollers in order that the size of the particles flowing to the collecting means may be varied to any desired size.

3. A crushing apparatus as set forth in claim 1 in which the spacing between each pair of rollers is adjustable by means of floating bearings and spring means effectively biasing said rollers apart.

4. In a crushing apparatus for producing particles of predetermined uniform size from bulk material having elements of varying size without electrostatically charging the particles produced, the combination of a housing, a container having an opening through which the elements of varying size flow, a plurality of vertically spaced cooperating pairs of rollers positioned within the housing and aligned in pairs below the opening, each pair of rollers having a spacing therebetween corresponding to the size of the elements to be crushed therebetween, a collecting means for receiving the particles after they have passed between all of said pairs of rollers, a distributing roller positioned adjacent the opening in said container for feeding the particles of varying size to a first pair of the cooperating rollers, a flow regulating plate rigidly mounted upon said housing and having a bottom

edge positioned adjacent said distributing roller near the opening in said container, the bottom edge of said plate being provided with a plurality of spaced openings in order to feed the elements to said first pair of rollers

- 5. at a preselected rate, the spacing between each successive pair of rollers becoming increasingly smaller as the elements pass from one pair of rollers to the next whereby all elements of the material within said container which are smaller than the spacing between the final pair of
- 10 rollers pass directly to the collecting means without being comminuted and all other elements are comminuted only by those pairs of rollers which are spaced apart by a distance less than the size of the elements, thereby to minimize the friction on the comminuted particles and to
- 15 reduce the electrostatic charges on the particles received by the collecting means.

5. A crushing mechanism as set forth in claim 4 in which the spacing between each of the pairs of rollers is adjustable by means of floating bearings and spring means effectively biasing said rollers apart.
